UNITED STATES PATENT OFFICE.

WILLIAM H. BAKER, OF CENTRAL FALLS, RHODE ISLAND, AND FREDERIC E. KIP, OF MONTCLAIR, NEW JERSEY.

LOOM.

SPECIFICATION forming part of Letters Patent No. 655,645, dated August 7, 1900.

Application filed January 6, 1900; Serial No. 411. (No model.)

To all whom it may concern:

Be it known that we, WILLIAM H. BAKER, residing at Central Falls, Providence county, Rhode Island, and FREDERIC E. KIP, residing at Montclair, Essex county, New Jersey, citizens of the United States, have invented certain new and useful Improvements in Looms, of which the following is a specification.

This invention relates to weft or filling changing or supplying mechanism for looms, and particularly to such as feed or supply bobbins in weft or bobbin holders or cases to the shuttle of a loom automatically as required.

15 The present invention includes an improved shuttle to receive the weft or bobbin case, an improved weft or bobbin case, improved electrical devices whereby a circuit is closed when the weft on the bobbin is nearly 20 or quite exhausted, an improved rotary magazine for carrying the weft or bobbin cases and bobbins, and improved means for controlling and operating said magazine.

In the accompanying drawings, which illustrate an embodiment of the invention, Figure 1 is a side elevation, on a relatively-small scale, of a loom embodying the invention. Fig. 2 is a side view of the magazine and adjacent parts, partly in section. Fig. 2^a is a 25 fragmentary view of the end of the magazine opposite to that seen in Fig. 2, and Fig. 3 is a sectional front elevation of the magazine and adjacent parts. Fig. 4 is a side elevation of the shuttle, containing a bobbin-case and bobbin. This view is on a larger scale than Figs. 2 and 3. Fig. 5 is a much-enlarged fragmentary sectional view of the shuttle, bobbin, and bobbin-case. Fig. 6 is an enlarged plan view of the bobbin-case, partly 35 in section; and Fig. 7 is an end view of the same. Fig. 8 is a view showing the spindle detached. Fig. 9 is a sectional view of the bobbin or weft holder detached. Fig. 10 illustrates a slightly-modified form of the magazine-mechanical device. Fig. 11 is a view illustrating how the contact-terminal in the bobbin is held against the centrifugal force tending to throw it out during the winding. Figs. 12 and 13 are views illustrating a construction wherein the spindle in the bobbin-case 45 is dispensed with. Figs. 14 and 15 are views

showing how mechanical controlling means employing a feeler may be used in place of electrical controlling means.

1 is the loom-frame. 2 is the breast-beam, 55 forming a part thereof. 3 is the lay. 4 is one of the lay-swords. 5 is the reed carried by the lay. 6 is the crank-shaft, which imparts vibrating movements to the lay, and 7 is one of the connecting-rods which couple 60 the cranks of the crank-shaft to the lay-swords. All of the above parts are common in looms.

Mounted on a suitable bracket 8 on the loom-frame is a rotary holder or magazine M 65 for the bobbin-cases 9, and this magazine is rotated by a belt 10, which is driven from a sheave or pulley 11 on a shaft of the loom, the crank-shaft 6 being the one employed herein. The belt 10 is not so tight but it may slip on 70 the sheave or pulley 12 on the magazine when the latter is held against rotation, as it is, habitually, by a fixed detent 13, which occupies a position in front of that bobbin-case 9 in the magazine which is directly over the 75 shuttle-box 15 on the lay when the latter is in its advanced position, as seen in Figs. 1 and 2.

The magazine M has a boss 16, Fig. 3, rotative about a fixed spindle 17 in the bracket 80 8, a head 18 on said boss, and arms 19 projecting from said head parallel with the axis of the magazine. The bobbin-cases 9 are supported at one end by spring-fingers 20, secured to the outer face of the head 18, and at 85 the other end by spring-plates 21, secured to the respective ends of the arms 19. These latter occupy positions between the respective bobbin-cases in the magazine and alternate with them.

90 The magazine may be of such size as to take in any reasonable number of bobbin-cases, but as herein shown it contains twelve. It may be said here that the bobbin-case is cylindrical, and in order that it may be properly placed in the magazine without difficulty it has at one end a recess or gain 22, which fits a squared part of the recess in the head 18 when the bobbin-case is properly placed.

95 The detent 13 arrests the rotation of the 100 magazine when the shuttle 24 is in the shuttle-box 15, directly under the lowermost bob-

bin-case in the magazine. The shuttle is open at the bottom, and the lay at the bottom of the shuttle-box has also an opening 14 under the shuttle, (see Fig. 2,) so that in supplying a fresh bobbin-case from the magazine the fresh case may be driven downward, so as to knock from the shuttle the case containing the exhausted bobbin and take its place. The means employed for driving the bobbin-case down into the shuttle consists of a driver 25, comprising a lever fulcrumed on the loom-frame at 26 and having a head 27 on its longer arm, which extends into the magazine at its open inner end and stands directly over the lowermost bobbin-case in the magazine. To the other and shorter arm 23 of the lever 25 is hinged the armature-lever 28 of an electromagnet 29, mounted on the loom-frame. When this magnet is excited, it draws down the armature-lever into the path of a tappet 30 on the lay, and when the lay beats up said tappet impinges on the armature-lever and through it rocks the lever 25, causing its head 27 to descend upon and drive down the bobbin-case below it from the magazine into the shuttle in the box below, thus displacing the bobbin-case therein. A suitable spring, as 31, normally upholds the driver.

The specific construction of the shuttle, the bobbin-case, the bobbin, and the electrical appliances will now be described.

As before stated, the shuttle has an opening at the bottom as well as at the top, the cavity of the shuttle extending down through it, and in the shuttle, at each end of said cavity, is a pair of laterally-spaced spring-jaws 32 to hold the bobbin-case 9 in place. In the lateral faces of the bobbin-case, at its respective ends, are vertical grooves 33, which are engaged by said jaws. Thus the bobbin-case is held in place with sufficient firmness, but may be displaced downward by the incoming case from the magazine. As before stated, the bobbin-case is cylindrical, and it has (in the principal views) a spindle 34, hinged in the case at its metallic head. This spindle is seen detached in Fig. 8. On it is a sliding metal washer or disk 35, backed by a spring 36, which is between said disk and the head of the spindle. The metallic bobbin-case is in two parts, connected together, but insulated from each other electrically by insulating material 37. (Seen clearly in Figs. 5 and 6.) Consequent upon this construction one end of the bobbin-case—that at the left in Figs. 5 and 6—is electrically connected when the bobbin-case is in the shuttle, through the spring jaws 32 and a conductor 38, with a metal contact-plate 39 on the side of the shuttle at that end, and the other end of the bobbin-case is connected electrically through the spring jaws 32 at that end of the shuttle and a conductor 40 with a metal contact-plate 39^X on the shuttle at that end of the latter. The insulation of the two sections of the bobbin-case may be effected by causing one section to telescope with the other and interposing

the insulating material 37, as seen in Figs. 5 and 6.

The construction of the bobbin or weft holder 42 is best seen in Figs. 5 and 9. It may be of any suitable form. As here shown, it is tubular and slips over the spindle 34, and it has at its butt an exteriorly-placed flanged metal ring 43 and an interiorly-placed metal ring 44. When pushed onto the spindle, the ring 44 bears on the disk 35 and is in electrical connection therewith, and the flange on the outer ring 43 wipes over and engages the free end of the metal spring 41, mounted in the bobbin-case and electrically connected with the section thereof at the right in Figs. 5 and 6. This spring 41 is in the nature of a conductor as well as a retainer for the bobbin.

Mounted in a longitudinal slot in the butt 85 portion of the bobbin is a spring-actuated contact-lever 45, fulcrumed at 46, the longer arm of which is held up into contact with the inner face of the outer ring 43 by a spring 47, connected electrically with the inner ring 44. The free end of the spring 47 contacts electrically with the lever 45 between the fulcrum-point 46 and the ring 43. The shorter arm 48 of the lever 45 projects, under these conditions, (see Fig. 9,) into the bore or hole 95 of the bobbin which is to receive the spindle 34, and when the bobbin is on the spindle (see Fig. 5) said arm 48 comes opposite to a recess 34^X of some kind in the spindle, as clearly shown in Figs. 6 and 8. The purpose 100 of this shorter arm on the contact-lever will be hereinafter explained.

The magnet 29 and a generator 49, Fig. 3, are in a normally-open electric circuit represented by conductors 50, which have spring-contact terminals 51 and 51^X at the side of the shuttle-box 15, these box-terminals being so placed as to be put into electric contact, respectively, with the plates 39 and 39^X on the shuttle when the latter enters the box. Now 110 if the long arm of the contact-lever 45 be pressed into contact with the outer ring 43 on the bobbin and the shuttle is in the shuttle-box the current will flow from one pole of the generator 49 to and through the coils of 115 the magnet 29, thence to the spring, box-contact 51, thence to the contact-plate 39 on the shuttle, thence by conductor 38 and one pair of jaws 32 to the section of the bobbin-case seen at the left in Figs. 5 and 6, thence through 120 the head of the spindle, the spring 36, and the washer 35 to the inner ring 44 on the bobbin, thence through the spring 47 to the contact-lever 45, thence to the outer flanged ring 43 on the bobbin, and through it and the retaining spring plate 41 to the section of the 125 bobbin-case at the right, thence through the jaws 32 at that end and the conductor 40 to the contact-plate 39^X on the shuttle, thence to the spring-box terminal 51^X, and thence 130 back to the other pole of the generator.

The contact-lever 45 is so bent or curved outward that when it makes contact with the ring 43 it projects out through the slot in the

bobbin; but when the weft or filling *w* is wound on the bobbin, as seen in Fig. 5, the lever is held pressed inward, so as to keep it out of contact with the ring 43 and also to hold the shorter arm 48 of the lever back out of the bore or hollow in the bobbin.

When the weft or filling *w* is nearly exhausted from the bobbin, the spring 47 forces the lever 45 out and into contact with the ring 43, thus closing the operating-circuit at this point, and then when the shuttle enters the shuttle-box 15 the circuit will be completed through the magnet 29, the armature-lever will be moved into the path of the tappet 30 on the lay, and the movement of the lay will cause the driver-head 27 to drive a fresh bobbin-case from the magazine down into the shuttle-box, displacing the exhausted one therein. When the lower bobbin-case is displaced from the magazine and the head of the driver is retracted, the constantly-running belt 10 will rotate the magazine M until the next bobbin-case therein comes to a bearing on the detent 13. The belt will slip by preference on the sheave 12.

The shuttle is cut down at the side, so as to permit the filling or weft-thread from the bobbin to take its proper place, said thread being primarily threaded through a guiding-eye 9^X in the bobbin-case. The several threads from the bobbins in the magazine M may be led out and attached to a suitable holder 52 thereon, as seen in Fig. 3.

Fig. 10 shows how the armature-lever may be made to support a lever 28^X, pivotally coupled to the arm 23 of the driver, this lever 28^X taking the impact of the blow from the tappet 30 and relieving the armature-lever of same.

Figs. 12 and 13 show a construction where the bobbin or weft holder is mounted in the bobbin-case without a spindle. The points of difference between this construction and that before described will be explained. The bobbin 42 in this construction is the same as that seen in Fig. 9, except that the outer ring 43^X is grooved and embraced by spring-jaws 53, mounted on and electrically connected with the section of the bobbin-case at the left, while the inner ring 44^X is in contact electrically with an upturned end on the spring-plate 41, which has the effect to put the spring 47 in electric contact with the right-hand end or section of the bobbin-case. Otherwise the construction is the same as before described.

In winding the weft or filling on a bobbin or weft holder having a contact-spring held out of contact (so as to break the circuit) by the overwrapped yarn it is found that the centrifugal force developed by the rapid rotation of the bobbin on the spindle of the winding-frame tends to throw out the contact-spring with a force greater than that exerted by the tension of the yarn, and consequently the yarn does not always maintain a break between the contacts. Therefore in order to

overcome this difficulty the contact-lever 45 of this invention is provided with the short arm or heel 48, extending into the bore of the bobbin, and when the latter is slipped onto the spindle 54 of the winding-frame, Fig. 11, the said spindle displaces said arm 48 outward, and by rocking the contact-lever on its fulcrum draws in the longer arm thereof and holds it drawn in against the centrifugal force tending to throw it outward, thus permitting the yarn to be wound on the bobbin properly. If the bobbin be afterward slipped onto a spindle, as 34, and this latter be provided with a recess 34^X, as described, the said recess will provide room for the arm 48, so that the lever 45 may make contact with the outer ring on the bobbin.

By "bobbin" as the word is herein used is meant any suitable form of holder for weft or filling. These holders have several names in the art. By "weft or bobbin case" as the phrase is herein used is meant any suitable holder for the bobbin.

It will be noted that we employ in carrying out our invention a bobbin case or holder which is driven down into the shuttle or weft carrier, and it may be explained that this avoids the necessity of employing what is denominated a "self-threading" shuttle. These latter do not thread themselves with certainty and are not well adapted to all kinds of weft or filling. In our construction it is only required to cut down the side of the ordinary shuttle to allow the thread or yarn from the eye 9^X on the bobbin-case to pass out. This eye 9^X will by preference be tubular, as seen in Fig. 6, and will have a pad or brush to put the proper tension on the yarn.

Our invention may be employed in connection with mechanical controlling mechanism in lieu of electrical—for example, that illustrated in our pending application, Serial No. 410, filed January 5, 1900. Such mechanical controlling mechanism is illustrated in Figs. 14 and 15, the former being a vertical longitudinal section of a part of the shuttle and the inclosed bobbin-case and the latter a plan of the same. In these views the free outer extremity of the lever 45 is provided with a detent-head 45^X, which is held down or in out of the path of a feeler 55 by the overwrapped filling or yarn on the bobbin; but when the filling is substantially exhausted the spring 47 presses said lever outward until its detent-head comes into the path of the feeler 55, when the latter will be pressed back, and thus cause the lay in beating up to actuate the driver 25. A feeler of this general character is illustrated in our beforementioned pending application, Serial No. 410, and a feeler to set in operation the weft-supply mechanism by impingement on an indicator when the weft in the shuttle in play is substantially exhausted is shown also in our pending application, Serial No. 4,221, filed February 6, 1900.

Fig. 8 shows a recess 34^X in the spindle 34,

which will be coincident with the arm or heel 48 when the bobbin is in place to allow the indicator 45 to operate when the weft or filling is substantially exhausted, and it is obvious that a spindle of this character would permit the indicator to operate if mounted in a shuttle as it would if in a bobbin-case.

In order to cushion the blow of one bobbin-case on another when the incoming case 10 drives out that in the shuttle, the bobbin-cases may be provided at each end with cushions 56, of rubber or similar material, as shown in Figs. 5, 6, 7, 13, and 14. These cushions may be constructed and applied in any 15 manner suited to effect the object sought and may be on the top or bottom of the case or on both the top and bottom.

By "weft-holder" as herein expressed is meant any receptacle holding weft or filling, 20 such as a weft or bobbin case containing weft or filling, or bobbin, butt-cop, cop, and the like containing weft or filling.

Although we have illustrated herein a weft-case or bobbin-case, we do not wish to give 25 undue prominence thereto, as our specially-constructed magazine is also adapted to take any known form of weft-holder.

Having thus described our invention, we claim—

30 1. In a loom, the combination with a rotary magazine for bobbin-cases, and bobbin-cases therein, each adapted to contain a tubular bobbin or weft-holder carrying weft, of the said weft-holders each provided with an indicator to indicate the substantial exhaustion of the weft, said indicator being a spring-actuated lever with an arm back of the fulcrum which is held out of the hollow of the bobbin by the overwrapped weft, means for 35 imparting to said magazine a tendency to rotate, a detent for arresting such rotation, a shuttle or weft-carrier adapted to receive the bobbin-case, a vibrating driver which drives a bobbin-case from the magazine down into the shuttle, and controlling intermediate 45 mechanism between the said indicator and the driver, whereby the latter is operated at proper times.

2. In a loom, the combination with a rotary 50 magazine for bobbin-cases, and bobbin-cases therein, each adapted to contain a tubular bobbin or weft-holder carrying weft, of the said weft-holders each provided with an indicator to indicate the substantial exhaustion of the weft, said indicator being a spring-actuated lever with an arm back of the fulcrum which is held out of the hollow of the bobbin by the overwrapped weft, means for imparting 55 to said magazine a tendency to rotate, a detent for arresting such rotation, a shuttle or weft-carrier adapted to receive the bobbin-case, a vibrating driver which drives a bobbin-case from the magazine down into the shuttle, and magneto-electrical controlling 60 mechanism between the said indicator and the driver, whereby the latter is operated at proper times.

3. In a loom, the combination with a rotary magazine to hold bobbin-cases, a continuously-running slip-belt for rotating said magazine, and a detent which normally arrests the rotation of the magazine, of the bobbin-cases, adapted to fit in said magazine, a bobbin or weft-holder adapted to fit into said bobbin-cases and each provided with an indicator to 70 indicate the substantial exhaustion of the weft, a vibrating lay and shuttle-box thereon, a shuttle adapted to receive the bobbin-cases, means for driving a bobbin-case from the magazine down into the shuttle, and intermediate controlling mechanism between the indicator and the said driving mechanism; whereby the latter is caused to supply bobbin-cases to the shuttle at proper times.

4. In a weft or filling supplying mechanism 85 for looms, the combination with a rotatively-mounted magazine having recesses with shoulders to receive and fit the bobbin-cases and spring-supports to hold them in place, of the said cases, each having a recess 22 in it near 90 its end to receive said shoulder for positioning the case in the magazine, for the purpose set forth.

5. In a weft or filling supplying mechanism 95 for looms, a bobbin-case to contain a bobbin, said case being of substantially-cylindrical form and having in it a spindle to carry and support the bobbin or weft-holder and an eye to guide the yarn, said spindle having in it a recess 34^X, and the said weft-holder provided 100 with a contact-lever and its spring, the lever having a short arm or heel, for the purpose set forth.

6. The combination with a shuttle having 105 spring-jaws at each end to embrace a bobbin-case, of the said bobbin-case provided with means to support within it a weft-holder and an eye for the yarn from the weft-holder, and having at its end and in its outer face a gain or recess 22, and a magazine having shoulders to fit the gained ends of the bobbin-cases, substantially as and for the purpose specified.

7. The combination with a shuttle having 115 spring-jaws to embrace and hold a cylindrical bobbin-case, and cut down from the top of the said bobbin-case, having within it means for holding and supporting a bobbin or weft-holder, an eye for the yarn from the bobbin, and a spindle having a recess 34^X, and a bobbin adapted to fit onto said spindle and provided with a spring-actuated contact-lever 120 provided with an arm 48, and a metal contact for said lever to impinge upon, substantially as and for the purposes set forth.

8. The bobbin or weft-holder having in it a longitudinally-extending slot, a contact-lever 45, fulcrumed in said slot and movable about its fulcrum radially in the weft-holder, and having an arm 48 back of said fulcrum, a 130 spring behind said lever and tending to press it outward normally, and a contact-piece to limit the movement of said lever.

9. The bobbin or weft-holder having in it a

- longitudinally-extending slot, a lever-indicator fulcrumed in said slot and movable radially to the axis of the weft-holder, and a spring acting on the longer arm of said lever 5 to press it outward, said indicator having an arm at the opposite side of the fulcrum which extends into the hollow of the bobbin when the longer arm thereof is pressed outward, for the purpose specified.
10. The combination with a bobbin or weft-holder having in it a slot, the lever-indicator fulcrumed therein and having its arm which is back of the fulcrum adapted to project into the hollow of the weft-holder when the 15 other arm thereof is pressed outward, and the spring which tends to press said arm outward, of a spindle to receive the bobbin having in it a recess which registers with said inwardly-projecting arm when the bobbin is in 20 place on the spindle, for the purpose specified.
11. The combination with a bobbin or weft-holder made tubular to fit on the spindle of a spinning or winding frame or apparatus and provided with a longitudinal slot, a lever-indicator fulcrumed in said slot and movable radially to the axis of the weft-holder, and a spring tending to press the said lever-indicator outward, said lever-indicator having a part which is projected into the hollow 25 of the weft-holder by the action of said spring, substantially as and for the purposes set forth.
12. The metallic bobbin-case provided with means for holding and supporting a bobbin or weft-holder, and composed of two sections 30 connected but electrically insulated from each other, for the purpose specified.
13. The combination with a shuttle having a pair of metallic spring-jaws at each end to support the respective ends of a bobbin-case, 35 and contact-plates at its ends connected electrically with the respective pairs of jaws, of the said bobbin-case, constructed of metal and in two connected sections, insulated electrically from each other, the line of separation 40 between said sections being transverse, substantially as set forth.
14. The combination of the sectional, metallic, bobbin-case, provided with a spring-plate 41, and means for supporting the bobbin, of a bobbin or weft-holder to fit into said case and provided with an indicator 45, its spring 47, a contact-ring 43, to form electrical contact with the indicator and the plate 41, and metal part 42, which is in electrical contact 45 with the spring 47, for the purpose specified.
15. The magazine, open at one end for the entry of the driver, and comprising an axial boss 16, a head 18, bars 19, which project 50 from the head 18 parallel with the axis of the magazine, spring-clips on the said head to support one end of the weft-holders, and spring-clips on the free ends of the bars 19 to support the other ends of the weft-holders.
65. 16. The rotatively-mounted magazine, having an axial boss, a single end or head, arms 55 on said head and extending therefrom substantially parallel with the axis of the magazine, and devices on said magazine for supporting therein the weft-holders, said arms 70 being situated between, and alternating with the weft-holders in the magazine.
17. The combination with a shuttle having in it two pairs of spring-jaws, one pair at each end, each jaw being provided on its clamping-face with a plurality of upright ribs, of a substantially-cylindrical bobbin-case adapted to fit into the shuttle between the said jaws, said case having at each end, on its sides, a plurality of upright grooves to receive the ribs 80 on the jaws, and on its upper face a cushion of soft, yielding material, substantially as set forth.
18. The combination with a shuttle having in it two pairs of spring-jaws, one pair at each end, each jaw being provided on its clamping-face with a plurality of upright ribs, of a substantially-cylindrical bobbin-case adapted to fit into the shuttle between the said jaws, said case having at each end, on its sides, a 85 plurality of upright grooves to receive the ribs on the jaws, and on its upper face a cushion of soft material, and having within it means for supporting and holding a bobbin, substantially as set forth.
95. 19. The combination with a shuttle, having in it two pairs of metal spring-jaws, one pair at each end, each being provided on its clamping-face with a plurality of upright ribs, of a metallic, sectional bobbin-case adapted to fit 100 into the shuttle and be clamped by said jaws so as to produce electrical contact, said bobbin-case having at each end a plurality of upright grooves in its sides to receive the ribs on the jaws, and on its upper face a cushion 105 of soft material, and having within it means for supporting and holding a bobbin, substantially as set forth.
20. A bobbin-case, having in it means for holding and supporting a bobbin and having 110 a cushion of soft material on its exterior surface, for the purpose specified.
21. A substantially-cylindrical bobbin-case of metal, having near its respective ends exteriorly-situated cushions, substantially 115 as and for the purposes set forth.
22. In a loom, a weft or filling replenishing mechanism comprising a magazine or holder for a reserve supply of weft or filling, said magazine being rotatively mounted and having 120 an axial boss, a single head or end, arms on said head and extending therefrom, substantially parallel with the axis of the magazine, and means for supporting weft-holders therein, said means comprising spring-clips 125 on said head and on the free ends of the respective arms which latter alternate with the weft-holders, means for effecting the transfer of a weft-holder from said magazine to the shuttle in play, and exhaustion-indicating devices controlling the operation of said transferring mechanism.

23. In a loom, a weft or filling replenishing mechanism, comprising a magazine or holder for a reserve supply of weft or filling, said magazine being rotatively mounted and having a single head or end, arms extending from the latter parallel with the axis of rotation, and clips on the said head and on the free ends of the respective arms for supporting the weft-holders, means for effecting the transfer of a weft-holder from said magazine to a shuttle in play, and electromechanical means for controlling the times of operation of said replenishing mechanism.
24. In a loom for automatically supplying a shuttle with a full weft-holder, the combination with a rotatable magazine and feeder for weft-holders, open at one end for the entry of the driver, and comprising an axial boss, a head, bars which project from the head parallel with the axis of the magazine, spring-clips on the said head to support one end of the weft-holders, and spring-clips on the free ends of the bars to support the other ends of the weft-holders.
25. The metallic weft-case provided with means for holding weft or filling, being substantially cylindrical in form and composed of two sections connected but electrically insulated from each other, for the purpose specified.
26. In a loom, the combination with a rotary magazine for weft-cases, and weft-cases therein, the said weft-case being constructed of metal and in two connected sections, insulated electrically from each other, and adapted to hold weft, means for imparting to said magazine a tendency to rotate, means for arresting said rotation as required, a shuttle adapted to receive the weft-case, a vibrating driver which drives a weft-case from the magazine into the shuttle, and electromechanical controlling means set in operation by the substantial exhaustion of the weft in the active shuttle for operating said driver to thereby furnish a new supply of weft or filling to said active shuttle at proper times.
27. In a loom, the combination with a shuttle-box, a shuttle having means to receive and hold a weft-case, said weft-case being constructed of metal and in two connected sections insulated electrically from each other, a weft-holder in the weft-case, a circuit-closer in said weft-holder, a driver, a weft-case feeder or magazine, having means to receive and hold both ends of a series of weft-cases, and actuating mechanisms for the said driver and the said magazine, whereby the latter is moved to bring one weft-case after another of the series into position between the driver and the shuttle-box, and the driver is made to transfer as required said weft-cases one after another from said magazine into the shuttle in the shuttle-box.
28. As an article of manufacture, a weft-holder having in it a slot, and a lever-indicator fulcrumed in said slot, said indicator having its shorter arm on the opposite side of the fulcrum adapted to extend into the hollow of the weft-holder when its longer arm is pressed outward.
29. The combination with a hollow bobbin or weft-holder provided with a longitudinal slot, of a lever-indicator fulcrumed in said slot and having an arm back of the fulcrum adapted to project into the hollow of the bobbin when the main arm of the indicator is pressed outward, and a spring which tends normally to press said main arm outward, substantially as and for the purpose set forth.
- In witness whereof we have hereunto signed our names, this 13th day of December, 1899, in the presence of two subscribing witnesses.
